FRICITION DRAFT GEAR

Donald F. Sproul, Chicago, Ill., assignor to Cardwell-Westinghouse Company, a corporation of Delaware

Application May 24, 1935, Serial No. 23,225

10 Claims. (Cl. 213—32)

This invention relates to draft gears and more particularly to draft gears of the friction type.

One of the objects of the invention is the provision of a new and improved draft gear having novel means for increasing the frictional resistance to the compression of the gear.

Another object of the invention is the provision of new and improved wedge mechanism for use in draft gears.

10 A further object of the invention is the provision of novel draft gear having new and improved means for positively releasing the wedge mechanism upon the release of the gear.

Other objects of the invention are the provision of a new and improved gear that is inexpensive to manufacture, easily assembled, efficient in operation and which is not likely to become broken or get out-of-repair.

Other and further objects and advantages of the invention will appear from the following description taken in connection with the accompanying drawings, in which:

Fig. 1 is a horizontal section of the center sills and draft gear of a railway car showing the gear in extended expanded position;

Fig. 2 is a section on the line 2—2 of Fig. 1 but showing the gear compressed;

Fig. 3 is a section on the line 3—3 of Fig. 2;

Fig. 4 is an end view of a modified form of the outer annular wedge means or ring;

Fig. 5 is a section on the line 5—5 of Fig. 4;

Fig. 6 is a perspective view of the inner wedge member;

Fig. 7 is a perspective view of the intermediate wedge member;

Fig. 8 is a perspective view of the outer wedge means or ring; and

Fig. 9 is a perspective view of the outer wedge or thrust member.

40 With the increase in the capacity of railway cars, the increased capacity for draft gears to be used on these cars becomes necessary. But for lack of space on the car for containing the gear it becomes necessary to increase the capacity of

45 the gear without increasing its overall dimensions. This presents a problem difficult of solution. High capacity gears have been proposed but more or less difficulty has been experienced in so

constructing the gear that it will have a proper 50 release. The present invention seeks to remedy this difficulty by the provision of a high capacity gear having positive means operating directly on the wedging mechanism for releasing said mechanism.

55 Referring now to the drawings, the reference

character 10 designates generally the draft gear which is adapted to occupy the conventional draft gear pocket 11 between the center sills 12 and 13 of a railway car. The draft lugs are shown at 14 and 15 and the buffer lugs at 16 and 17. If desired, plates 18 and 19 may be inserted between the ends of the gear 10 and the draft and buffer lugs, respectively. The draft gear comprises a casing or barrel 21 which is preferably though not necessarily circular in cross section. 10 The draft yoke 20 surrounds the plates and gear in the usual manner. Since the details of the means for mounting the gear on the car constitute no part of the present invention, it is not thought necessary to further illustrate or describe the same.

The casing 21 is provided with a base 22 which may comprise a flange 23 extending about the forward end of the casing 21. Reinforcing ribs 24 may be provided for reinforcing the flange 23. 20 The base constitutes the bottom wall of the casing 21 and this wall is provided with what for convenience of description will be termed an inwardly extending axial depression 25 having an axial opening 26 for receiving a bolt 27 for holding the gear in assembled relation, as will presently appear. The inner end of the casing 21 is open and is provided on its interior with a friction surface 28. Suitable friction elements are provided for frictionally engaging the surface 28 30 for resisting the compression of the gear. These elements comprise an inner wedge member 29 having a flat base 31 and an annular inclined wedging surface 32 facing outwardly.

This wedge member is preferably annular and has the axial opening 33 into or through which a reduced extension 34 of an intermediate wedge member 35 extends. The wedge member 35 has the wedge faces 36 and 37, preferably annular, facing in opposite directions. The intermediate 40 wedge member 35 is also provided with an axial opening 38 through which extends an extension 39 of an outer wedge or thrust member 41. The outer wedge or thrust member 41 is provided with an inwardly facing annular wedge face 42. The 45 extension 39 of the outer wedge member 41 is hollow and has a partition 43 which is provided with an axial opening 44 in axial alignment with an opening 45 in the end wall of the extension 39. The bolt 27 extends through the openings 50 45 and 44 and is provided with a nut 46 for engaging the partition 43 for holding the parts in operative position when the parts are assembled, as will presently appear.

Suitable means are provided for engaging the 55

wedging faces or inclined surfaces of the wedge members. In the form of construction shown, the inner and outer wedging means 47 and 48 are employed for this purpose. Each of these 5 wedging means is preferably in the form of a split ring, the inner means 47 having the inclined wedging faces 49 and the inclined wedging faces 51 which engage the corresponding wedging surfaces 32, 36 on the inner wedge 10 member and intermediate wedge member respectively. The outer wedging means 48 likewise have the inclined wedging faces 52 and 53 facing in opposite directions which engage the wedging faces 37 and 42 of the intermediate 15 wedge member 35 and outer wedge or thrust member 41. Each of the wedging means or elements 47 and 48 is preferably cast with radial slots 54 (see Fig. 8) which will give them more or less resiliency.

20 After the casting operation, each of the wedging means is split through one of the slots 54, as shown at 55, thereby forming a split ring, as shown in Fig. 8, for permitting the expansion thereof when the gear is compressed.

25 Appropriate resilient means are provided for resisting the inward movement of the wedging mechanism whereby the frictional elements 47 and 48 are forced outwardly into frictional engagement with the friction surface 28 of the 30 casing. As shown, a plurality of concentrically arranged springs 56, 57 and 58 are employed for this purpose.

The spring 56 engages the surface 31 of the wedge member 29 at one end and is seated on 35 the end wall of the casing at its other end. This spring surrounds the springs 57 and 58 and functions to resist the inward movement of the wedge member 29 whereby upon compression of the gear, the friction element 47 40 will be forced into frictional contact with the friction surface 28 of the casing.

The intermediate spring 57 engages the inner 45 end of the intermediate wedge member 35 and yieldingly resists its inward movement whereby when the gear is compressed, a wedging action will be set up between the wedging means 48 and this intermediate wedge member. As a result of this wedging action, the wedging means 48 will be forced outwardly into frictional contact with the interior of the casing. When 50 the gear is compressed, the frictional resistance between the outer wedge member 48 and the casing will absorb a great amount of the energy of the shock, thereby relieving the spring 56 and wedging means 29 and 47 of a considerable 55 amount of the shock and consequently the capacity of the gear is very greatly increased without necessitating any change in the angles of the wedge faces or increasing the size or capacity of the springs. The spring 57, since it 60 engages the inner end of the extension 34, also functions to release the wedging action between the inner wedging means 47 and the intermediate wedge member 35—that is, it releases what for convenience of description will be termed 65 the auxiliary wedging mechanism.

The inner spring 58 functions to resiliently 70 resist the inward movement of the outer wedge member 41 but its principal function is to release the wedging action of what may be termed the main wedging system in that it releases or loosens the wedge member 41 upon the release of the gear, and this in turn releases the annular wedge means 48. The springs all cooperate 75 to restore the parts to normal position after

release of the gear. It will thus be seen that the springs all operate independently of each other, that is, they operate in parallel.

In the operation of the device, when the gear is compressed, the spring 57 will tend to resist the inward movement of the intermediate wedge member 35 which will tend to cause the inclined surface on the wedge members to force the annular wedging means 48 outwardly into frictional engagement with the gear casing, thereby 10 resisting further inward movement of the friction mechanism. The outer spring 56 operates simultaneously to yieldingly resist inward movement of the inner wedge member 29 which will cause a wedging action on the wedging means 15 47 forcing the same into frictional engagement with the inner wall of the casing.

Upon release of the gear, the inner spring 58 will act directly upon the outer wedge or thrust member 41 for releasing this member and simultaneously the spring 57 will act directly on the intermediate member 35 for releasing the same. Since the dynamic wedging force or energy that is transmitted to the inner wedging means 47 is less than that transmitted to 25 the outer wedge element 48, this inner wedging member may be of composition material, as shown by the wedge element 59 in Figs. 4 and 5. The composition wedge element is split as at 61 but differs from the wedge element 47 in that 30 it is not provided with radial slots as in the other construction. The ring 59, however, may be substituted for either the friction means 47 or 48, or both, if desired.

It will thus be seen that with either types 35 of wedging members there are in effect what may be termed two systems of wedging mechanisms, one including the outer wedging means 48 and the other the inner wedging means 47 and that these wedging means are independently released by the springs 57 and 58 operating on the intermediate and outer wedge members respectively.

After the gear is assembled, the outer and inner wedging means if of metal may during 45 use break up into segments along the lines of the grooves 54. The segmental wedge means will function the same as the split ring.

The capacity of the gear may be increased materially by decreasing the angles of the inclined surfaces of one or both of the wedging means 47 or 48. These angles cannot, of course, be decreased to such an extent that they may not be released by the springs 57 and 58, as otherwise the gear will stick when compressed. 55

I claim as my invention:—

1. In a draft gear, a casing, wedge mechanism including inner, outer and intermediate wedge members within said casing, a plurality of springs, one for each wedge member engaging 60 said members, respectively, and operating independently of each other, for resisting the inward movement of said mechanism during compression and for releasing said wedge members upon the release of said gear, and friction means 65 between said wedge mechanism and said casing.

2. In a draft gear, a tubular casing circular in cross section, wedging mechanism within said casing, said mechanism comprising an inner wedge member having an axial opening and an 70 annular wedging surface facing outwardly, an intermediate wedge member having an axial opening and an extension projecting into said first-mentioned axial opening, said last-named member having a pair of annular inclined sur- 75

faces facing in opposite directions, an outer wedge member having an annular outwardly facing wedging surface, said last-named member having an elongated reduced extension extending inwardly through said axial openings, a pair of split annular wedge rings for engaging said inclined and wedging surfaces, and outer, intermediate and inner concentrically arranged springs within said casing for engaging said inner wedging member and said extensions, respectively, for resisting the inward movement of the wedging members and for restoring the parts to normal position upon release.

3. In a draft gear, a casing, friction mechanism within said casing, said members comprising an annular inner wedge member having an axial opening therethrough and provided with an outwardly facing wedging surface, an intermediate wedge member having a reduced extension extending into said opening and provided with an axial aperture in alignment with said opening, said intermediate wedge member having a pair of wedging surfaces facing in opposite directions, a thrust member having an annular inwardly facing wedge surface and provided with a reduced extension extending rearwardly into said aperture, inner and outer wedge means having annular wedging faces for engaging said wedging surfaces whereby when said gear is compressed said means will be forced radially outward into frictional engagement with the interior wall of said casing, and springs engaging said inner wedge member and said projections respectively.

35 4. In a draft gear, a casing, a plurality of wedging means within said casing, each having two inclined wedging surfaces facing in opposite directions, wedging members engaging said faces, and a spring for each member for resisting inward movement of said members and for positively releasing a plurality of said members upon the release of said gear, said springs operating independently of each other.

5. In a draft gear, an intermediate wedge member having two conical wedging surfaces facing in opposite directions from each other, said member having a reduced elongated axial extension having a cylindrical exterior surface, said member having an axial opening extending therethrough.

45 6. In a draft gear, a casing having an open and a closed end, a cylindrical depression in its closed end provided with an axial bore, a pair of expandible friction means for frictionally engaging the interior of said casing, inner, outer and intermediate wedge members for expanding

said means upon the compression of said gear, said outer and intermediate wedge members having reduced concentric extensions extending inwardly and provided with axial openings, the extension of said outer wedge member being hollow and provided with a partition having an axial opening in alignment with said openings, and a bolt engaging said depression and said partition for limiting the expansion of said gear and resilient means for resisting compression of said gear and for restoring the parts to normal position after release.

5 7. In a draft gear, a casing, two friction shoes within said casing for frictionally engaging the inner surface of said casing, inner, outer and intermediate wedging elements engaging said shoes, one of said elements having wedging surfaces facing in opposite directions, spring means for resisting the inward movement of said shoes and wedging elements and independently engaging each of said wedging elements and operating in parallel for positively releasing the outer wedge element.

10 8. In a draft gear, a casing having a friction surface, inner and outer friction shoes for frictionally engaging the inner wall of said casing, means for forcing said friction shoes into frictional engagement with said casing upon the compression of the gear comprising at least three wedging members, and a spring for each of said 20 wedging members and engaging the same, said springs operating in parallel.

25 9. In a draft gear, a tubular casing, inner and outer friction members, each of said members having annular wedging surfaces, at least three 35 annular wedge elements engaging said surfaces, and at least three concentric springs of substantially the same lengths within said casing engaging said wedge elements, respectively, and all of said springs being seated against one end of 40 said casing for resisting the compression of said gear and for restoring the parts to normal position after compression, all of said springs operating in parallel.

45 10. In a draft gear, a casing, at least three 45 wedging elements, one of which has oppositely directed wedge faces, within said casing, friction shoes engaging said elements and said casing, spring means for resisting compression of said gear and for restoring the parts to normal 50 position after release, said means comprising a plurality of springs, one for engaging each of said elements, said springs operating in parallel and being of substantially the same length.

55 DONALD F. SPROUL.
